OXIDATION OF BENZODIAZEPINES WITH
RUTHENIUM TETROXIDE

ABSTRACT OF THE DISCLOSURE

Conversion of 1,4-benzodiazepines (A) and tetrahydro-1,4-benzodiazepin-2-ones (B) into 2,3-dihydro-1,4-benzodiazepin-2-ones (C) by oxidation of (A) or (B) with ruthenium tetroxide. (C) are useful as anticonvulsants, muscle relaxants and sedatives.

BACKGROUND

The reagent ruthenium tetroxide was first discovered more than a century ago. However, it appears that little effort was made to explore its capabilities as evidenced by the relative paucity of literature articles reporting on studies of reactions with ruthenium tetroxide. Certain workers in the art [Berkowitz et al., J. Am. Chem. Soc., 80, 6682 (1952)] have shown that ruthenium tetroxide is usable as an oxidant. However, it was not known until the discovery by the present applicants that ruthenium tetroxide could be efficaciously utilized in oxidizing amino group containing compounds such as benzodiazepines into corresponding compounds containing the carbonyl group in position-2 and the so-called Schiff's base, i.e. the

radical. This discovery is particularly surprising due to the relative difficulty of converting a $-\text{CH}_2-$ grouping in a heterocyclic amino to a $\text{C}=\text{O}$ grouping and the well known propensity of the

radical to be unstable under conditions of the type inherent in an oxidation reaction.

DETAILED DESCRIPTION OF THE INVENTION

As is evident from the above, the present invention relates to the oxidation of benzodiazepines with ruthenium tetroxide. In one aspect, the present invention relates to a process which comprises oxidizing a compound of the formula:

wherein A is selected from the group consisting of

B is selected from the group consisting of halophenyl, phenyl, nitrophenyl, pyridine and pyrimidine, R and R₁ are selected from the group consisting of hydrogen, halogen, nitro and trifluoromethyl, R₂ is selected from the group consisting of hydrogen and lower alkyl and R₃ is any suitable group which is stable to oxidation under the oxidation conditions employed.

2

with ruthenium tetroxide whereby to prepare the corresponding compound of the formula:

II

wherein B, R, R₁, R₂ and R₃ are as described hereinabove.

In another aspect, the present invention relates to oxidizing compounds of the formula:

III

wherein B, R, R₁, R₂ and R₃

with ruthenium tetroxide to thereby obtain the corresponding compound of the Formula II above.

Illustrative of typical radicals represented by the character R₃ which are stable under the oxidation conditions described herein to effect the preparation of compounds of the Formula II above are the hydrogen radical, the lower alkyl radical, the halo lower alkyl radical, e.g. chloropropyl, bromoethyl and the like, a basic side chain containing radical such as the dilower alkyl-amino-lower alkyl radical (dimethylaminoethyl, diethylaminoethyl, dimethylaminopropyl and the like), or any other radical which would be stable under the oxidation conditions utilized; that is to say, that would be unaffected by oxidation in the manner described herein utilizing ruthenium tetroxide.

By the term lower alkyl as utilized herein, both branched and straight chain C₁—C₇, preferably C₁—C₄, hydrocarbon groups are contemplated such as methyl, ethyl propyl, isobutyl and the like. By the term halogen as utilized herein, all four forms thereof are contemplated unless otherwise specified, e.g. chlorine, bromine, iodine and fluorine.

A particularly advantageous process aspect of the present invention results in the preparation of compounds of the Formula II above wherein R and R₂ are hydrogen and B is phenyl or halophenyl, preferably, 2'-halophenyl, most preferentially, 2'-fluorophenyl. In a more preferred embodiment R₁, R₂ and B are as above and R₁ is halogen, preferably chlorine or bromine, most preferably, chlorine. In the most preferred embodiment, R, R₁ and R₂ represent the groups preferred above, B is the phenyl group, R₃ is selected from the group consisting of hydrogen, lower alkyl, most preferentially, methyl and dilower alkyl amino lower alkyl, most preferentially, diethylaminoethyl. If B is pyridyl, a 2-pyridyl radical is preferred.

In either of the process aspects set forth above, the oxidation with ruthenium tetroxide proceeds readily and easily to the desired product of the Formula II above. In a preferred aspect, ruthenium tetroxide is added to the reaction zone in a molar excess. Preferably, the reaction is effected at below room temperature, e.g., at a temperature range of from about -20° to about 15°, most preferably, from about 0° to about 10°. The reaction proceeds most suitably in the presence of an inert inorganic solvent and among the many solvents suitable for the purposes of the present invention there may be included halogenated aliphatic hydrocarbons such as chloroform, dichloromethane and the like.

Advantageously, after the reaction is permitted to

3

proceed for the time necessary to effect the desired end, i.e. to the point where compounds of the Formula II above are prepared, any suitable reagent may be added to the reaction medium to destroy any excess ruthenium tetroxide present therein. A preferred reagent for this purpose is a lower alkanol such as 2-propanol.

The compounds of the Formula II above are known compounds and are useful as anticonvulsants, muscle relaxants and sedative agents. Their pharmacological usefulness is well documented in the literature.

When pursuing the reaction described above, i.e. the oxidation of a compound of the Formula I or III above wherein R₂ is hydrogen with ruthenium tetroxide, it has been observed that there is obtained as a minor product, a compound of the formula:

IV

wherein R, R₁, R₃ and B are as above.

As is noted above, an excess of ruthenium tetroxide is preferentially utilized in the preferred embodiment. If a slight excess is utilized, the compound of the Formula II is the major product and its preparation is preferred. If a great excess of ruthenium tetroxide is utilized, the compound of the Formula IV can be obtained in major amounts. The amount of ruthenium tetroxide utilized to achieve the desired end is readily ascertainable by those skilled in the art. As the particularly preferred embodiment of this invention relates to the preparation of a compound of the Formula II above, it is of course evident that a slight excess of ruthenium tetroxide is preferentially utilized for the purposes of the present invention.

Compounds of the Formula IV above can also be prepared by treating the corresponding compound of the formula:

wherein R, R₁, R₃ and B are as above with ruthenium tetroxide in the manner described above.

Compounds of the Formula IV above can be converted into the known compounds of the Formula II above or into the corresponding compounds which contain a methylene group in position-2 with lithium aluminum hydride according to known procedures.

The process of the present invention in a preferred embodiment therefore relates to a novel oxidation procedure for effecting the conversion of certain benzodiazepines into other 2,3-dihydro-1,4-benzodiazepin-2-ones in unexpectedly good yields and in a facile and convenient manner.

The following examples are illustrative but not limitative of the present invention. All temperatures are stated in degrees centigrade.

EXAMPLE 1

Into a 500 ml. 3-necked round bottom flask equipped with magnetic stirrer and immersed in an ice-salt bath at -10° was placed 7-chloro-2,3-dihydro-5-phenyl-1H-1,4-benzodiazepine (642 mg., 2.5 mmoles). A chloroform solution of ruthenium tetroxide (158 ml. of 0.07 M, 11 mmole, 4.4 equivalents) was added dropwise over a 30 minute period and stirred for an additional period of 30 minutes. 2-propanol (10 ml.) was added to the re-

4

action medium and the reaction mixture was filtered. The RuO₂ which precipitated was washed with hot tetrahydrofuran and the combined filtrate evaporated to dryness yielding 7-chloro-2,3-dihydro-5-phenyl-2H-1,4-benzodiazepin-2-one. After crystallization from carbon tetrachloride-hexane, the product melted at 215.0-217.0°.

EXAMPLE 2

Into a 500 ml. 3-necked round bottom flask equipped with magnetic stirrer and immersed in an ice-salt bath at -10° was placed 7-chloro-2,3-dihydro-1-methyl-5-phenyl-1H-1,4-benzodiazepine (732 mg., 2.7 mmole). A solution of ruthenium tetroxide (180 ml. of 0.054 M, 9.7 mmole, 3.6 equivalents) was added dropwise over a 30 minute period and stirred for an additional 30 minutes. 2-propanol (5 ml.) and water (200 ml.) was added to the reaction medium and the mixture was filtered through Celite. The filtrate was transferred to a separatory funnel and the chloroform layer retained. The aqueous layer was washed three times with chloroform. The chloroform washings were added to the said chloroform layer. The so-obtained medium was dried over magnesium sulfate, filtered and evaporated to a small volume. Hexane was added to the resulting medium. It was then allowed to stand. Crystals of 7-chloro-2,3-dihydro-1-methyl-5-phenyl-2H-1,4-benzodiazepin-2-one, M.P. 127-130.5° formed which was separated by filtration.

EXAMPLE 3

Into a 500 ml. 3-necked round bottom flask equipped with magnetic stirrer and immersed in an ice-salt bath at -10° was placed 2,3-dihydro-1-methyl-7-nitro-5-phenyl-1H-1,4-benzodiazepine (678 mg., 2.5 mmole). A solution of ruthenium tetroxide (165 ml. of 0.077 M, 12.7 mmole, 5.1 equivalents) was added dropwise over a 30 minute period and stirred for an additional 30 minutes. 2-propanol (5 ml.) was then added and the reaction mixture was filtered. The RuO₂ which precipitated was washed with chloroform and the combined filtrate evaporated to dryness yielding 2,3-dihydro-1-methyl-7-nitro-5-phenyl-2H-1,4-benzodiazepin-2-one. After crystallization from ethanol-water the product was found to have a M.P. of 153-158°.

EXAMPLE 4

Into a 250 ml. 3-necked round bottom flask equipped with magnetic stirrer and immersed in an ice bath was placed 2,3-dihydro-7-nitro-5-phenyl-1H-1,4-benzodiazepine (1.34 g., 5.0 mmole). A solution of ruthenium tetroxide (271 ml. of 0.074 M, 20 mmole, 4 equivalents) was added dropwise over a 30 minute period and stirred for an additional hour. 2-propanol (5 ml.) was added to the reaction medium and the resulting reaction mixture was filtered and washed with tetrahydrofuran. The combined filtrate was evaporated to dryness. There was obtained a yellow solid, which upon crystallization from ethanol afforded 2,3-dihydro-7-nitro-5-phenyl-2H-1,4-benzodiazepin-2-one as off-white prisms, M.P. 221-227°.

EXAMPLE 5

Into a 500 ml. 3-necked round bottom flask equipped with magnetic stirrer and immersed in an ice bath was placed 2,3-dihydro-1-methyl-7-nitro-5-(2-pyrimidinyl)-1H-1,4-benzodiazepine (944 mg., 3.33 mmole). A solution of ruthenium tetroxide (260 ml. of 0.058 M, 15 mmole, 4.5 equivalents) was added dropwise over a 30 minute period and stirred for an additional 30 minutes. 2-propanol (5 ml.) was added and the reaction mixture was filtered and evaporated to dryness. The resultant oil was crystallized from methylene chloride-hexane giving 2,3-dihydro-1-methyl-7-nitro-5-(2-pyrimidinyl)-2H-1,4-benzodiazepin-2-one, M.P. 194.0-196.5° dec.

The starting material 2,3-dihydro-1-methyl-7-nitro-5-(2-pyrimidinyl)-1H-1,4-benzodiazepine is not part of the present invention, but its preparation is disclosed herein in order that the disclosure may be complete.

To a solution of 54.4 g. (0.36 moles) of o-chlorophenyl acetonitrile in 900 ml. of anhydrous tetrahydrofuran, 17.2 g. (0.36 moles) of sodium hydride (50:50 by wt. in mineral oil) was added. The resulting mixture was heated to reflux for 30 min. while stirring. The temperature was lowered to 60° and a solution of 41.1 g. (0.36 moles) of 2-chloropyrimidine in 216 ml. of tetrahydrofuran was added slowly. The reaction mixture was then refluxed for 3 hrs. After cooling, 100 ml. of water was added cautiously and tetrahydrofuran was removed by distillation under reduced pressure. The residue was extracted with methylene chloride, washed with water and dried (Na_2SO_4). Removal of solvent by distillation gave a residue which was extracted twice with 375 ml. of hot hexane. The hexane insoluble fraction was crystallized from a mixture of benzene and hexane to give 2-(2-pyrimidyl)-2-(2-chlorophenyl)acetonitrile; M.P. 79-81°. Additional amounts of the product were obtained from the mother liquor and the hexane extract. Recrystallization of the product from hexane gave colorless rhombs melting at 81-82°.

To a solution of 3.0 g. (0.013 moles) of 2-(2-pyrimidyl)-2-(2-chlorophenyl)acetonitrile in 250 g. of dry tetrahydrofuran, 0.76 g. (0.016 moles) of sodium hydride (50 percent by weight in mineral oil) was added and the mixture stirred and refluxed for 2 hrs. It was then cooled to room temperature and stirred for 16 hrs. while passing a stream of dry air through the mixture. Methanol (10 ml.) and water (20 ml.) were added to destroy excess sodium hydride and the mixture was then concentrated under reduced pressure to remove tetrahydrofuran. On addition of water to the residue, 2-(2-chlorobenzoyl)pyrimidine crystallized (M.P. 124-7°). An additional amount of the product was obtained from the filtrate. Recrystallization from a mixture of benzene and hexane gave colorless plates of 2-(2-chlorobenzoyl)pyrimidine, M.P. 127-9°.

A solution of 11.9 g. of 2-(2-chlorobenzoyl)pyrimidine in 60 ml. of concentrated sulfuric acid was cooled to 0° and a solution of 3.1 ml. of 90 percent nitric acid in 7.7 ml. of concentrated sulfuric acid was added dropwise during 1 hr. The reaction mixture was then stirred for an additional hour at 0° and for 1 hr. at room temperature, then poured onto ice. On neutralization with dilute ammonia, a white solid formed. Filtration separated 2-(2-chloro-5-nitrobenzoyl)pyrimidine, M.P. 143-6°. Recrystallization from benzene gave light yellow rhombs melting at 147-9°.

A mixture of 2-(2-chloro-5-nitrobenzoyl)-pyrimidine (446.2 gm., 1.70 mols.), ethylenediamine (510 gm., 8.5 mols.) and anhydrous pyridine (1700 ml.) was stirred and heated on the steam-bath for 5 hrs. Most of the solvents were removed by concentration under reduced pressure, followed by successive co-distillation with xylene and toluene. The resulting tarry residue was mixed with methanol (200 ml.) and aqueous 3 N-sodium hydroxide. The crude product precipitated, and was recovered by filtration, washed with water, and dried. Purification was effected by addition of Woelm activity I neutral alumina (1 kg.) to a slurry of the product in methanol, followed by removal of the solvent under reduced pressure. The dried mixture of product and alumina was then continuously extracted with hot methylene chloride, in a Soxhlet extractor, until no further product was recovered in the extract (4-5 days were required). Filtration of the extract gave 2,3 - dihydro - 7-nitro-5-(2-pyrimidinyl)-1H-1,4-benzodiazepine (M.P. 222-224° C.).

A solution of 2,3-dihydro-7-nitro-5-(2-pyrimidinyl)-1H-1,4-benzodiazepine (147.7 gm., 0.55 mols.) and sodium methoxide (33.0 gm., 0.61 mols.) in anhydrous N,N-dimethylformamide (1300 ml.) was stirred for 1 hour at room temperature and was then treated dropwise with a solution of dimethyl sulfate (77.0 gm., 0.61 mols.) in dry dimethylformamide (260 ml.) during 2 hours, maintaining the temperature of the reaction mixture at 0-5° C., by cooling in an ice bath. Stirring was continued for 24 hours at room temperature, and then

the mixture was poured into ice water (6 liters). Dry ice was added until the mixture was approximately neutral (pH 5-6); the crude product was recovered by extraction with methylene chloride, and was obtained as a largely crystalline solid. This material was extracted with cold methylene chloride and filtered. The filtrate was passed through a bed of Woelm activity III neutral alumina (785 gm.). The methylene chloride eluate was evaporated, and the resulting residue was crystallized from benzene-hexane to give 2,3-dihydro-1-methyl-7-nitro-5-(2-pyrimidinyl)-1H-1,4-benzodiazepine (M.P. 179-181° C.). A further crop was obtained from the mother liquors. The product was recrystallized from methylene chloride-hexane as yellow rods, M.P. 181-183° C. (dec.).

EXAMPLE 6

Into a 500 ml. 3-necked round bottom flask equipped with magnetic stirrer and immersed in an ice-salt bath at -10° was placed 7-chloro-1,3,4,5-tetrahydro-5-phenyl-2H-1,4-benzodiazepin-2-one (681 mg., 2.5 mmole). A solution of ruthenium tetroxide (150 ml. of 0.067 M, 7.0 mmole, 2.8 equivalents) was added dropwise over a 30 minute period and stirred for an additional 30 minutes. 2-propanol (5 ml.) was then added and the reaction mixture was filtered and evaporated to dryness giving 7 - chloro - 2,3 - dihydro - 5 - phenyl - 2H - 1,4 - benzodiazepin-2-one which after crystallization from carbon tetrachloride-hexane melted at 215.5-217.5°.

EXAMPLE 7

A stirred solution of 0.5 g. (0.00166 M) of 7-chloro-1,3 - dihydro - 3 - hydroxy - 1 - methyl - 5 - phenyl - 2H-1,4-benzodiazepin-2-one in 12 ml. of chloroform cooled in an ice bath was treated with the dropwise addition of 35 51 ml. (0.00332 M) of a 0.0647 M ruthenium tetroxide solution. After 18 hrs., 15 ml. of water was added and the mixture was filtered through celite. The chloroform layer was separated, dried over anhydrous sodium sulfate and evaporated to dryness. To the oil so obtained there was added a mixture of dichloromethane and hexane (2:1). The precipitate which formed each time was removed. The mother liquors were then crystallized from ether and the product recrystallized from a mixture of dichloromethane and hexane to give 7-chloro-1-methyl-5-phenyl-1H-1,4-benzodiazepine-2,3-dione as white prisms, melting at 169-174°.

EXAMPLE 8

A stirred suspension of 3 g. (0.0105 M) of 7-chloro-1,3-dihydro - 3 hydroxy - 5 - phenyl - 2H - 1,4 - benzodiazepin-2-one in 10 ml. of CHCl_3 in an ice bath was treated with 200 ml. (0.013 M) of a 0.0647 M solution of ruthenium tetroxide in chloroform. After 18 hrs. at room temperature, 25 ml. of water was added and the solution was filtered through celite. A precipitate which then formed in the filtrates was removed by filtration and recrystallized first from ethyl acetate and then from a mixture of dichloro-methane and petroleum ether to give 7-chloro-5-phenyl-1H-1,4-benzodiazepine-2,3-dione as yellow plates melting at 243-251°.

EXAMPLE 9

A solution of 1 g. (0.00348 M) of 7-chloro-1,3,4,5-tetrahydro - 1 - methyl - 5 - phenyl - 2H - 1,4 - benzodiazepin-2-one in 25 ml. of chloroform was stirred in an ice bath and was treated with 108 ml. (0.00696 M) of a 0.0047 M solution of ruthenium tetroxide in chloroform over a 10-minute period. After standing 18 hours at room temperature an additional 75 ml. (0.00485 M) of ruthenium tetroxide was added and the reaction was allowed to stand for an additional 18 hours. Water (50 ml.) was added and the mixture was filtered through Celite. The chloroform layer was separated, dried over anhydrous sodium sulfate and evaporated to dryness. The residue was crystallized from ether to give 7-chloro-2,3-dihydro-

7

1-methyl-5-phenyl-2H-1,4-benzodiazepin-2-one as white prisms melting at 128-32°. An examination of the mother liquor by thin layer chromatography showed the presence of considerable amounts of 7-chloro-1-methyl-5-phenyl-1H-1,4-benzodiazepine-2,3-dione.

What is claimed is:

1. A process which comprises oxidizing a compound of the formula:

wherein Z is selected from the group consisting of carbonyl and methylene, A is selected from the group consisting of

and

with the proviso that when Z is carbonyl, A is

B is selected from the group consisting of halophenyl, phenyl, nitrophenyl, pyridine and pyrimidine, R and R₁ are selected from the group consisting of hydrogen, halogen, nitro and trifluoromethyl, R₂ is selected from the group consisting of hydrogen and lower alkyl and R₃ is selected from the group consisting of hydrogen, lower alkyl, halo-lower alkyl and diloweralkyl-amino lower alkyl

8

with ruthenium tetroxide whereby to prepare the corresponding compound of the formula:

5

wherein B, R, R₁, R₂ and R₃ are as described hereinabove.

2. A process as defined in claim 1 which comprises oxidizing 7-halo-2,3-dihydro-5-phenyl-1H-1,4-benzodiazepine with ruthenium tetroxide whereby to obtain 7-halo-2,3-dihydro-5-phenyl-2H-1,4-benzodiazepin-2-one.

3. A process as defined in claim 1 which comprises oxidizing 7-chloro-2,3-dihydro-5-phenyl-1H-1,4-benzodiazepine with ruthenium tetroxide whereby to obtain 7-chloro-2,3-dihydro-5-phenyl-2H-1,4-benzodiazepin-2-one.

4. A process as defined in claim 1 which comprises oxidizing 7-halo-2,3-dihydro-1-methyl-5-phenyl-1H-1,4-benzodiazepine with ruthenium tetroxide whereby to obtain 7-halo-2,3-dihydro-1-methyl-5-phenyl-2H-1,4-benzodiazepin-2-one.

5. A process as defined in claim 1 which comprises oxidizing 7-chloro-2,3-dihydro-1-methyl-5-phenyl-1H-1,4-benzodiazepine with ruthenium tetroxide whereby to obtain 7-chloro-2,3-dihydro-1-methyl-5-phenyl-2H-1,4-benzodiazepin-2-one.

6. A process as defined in claim 1 which comprises oxidizing 2,3-dihydro-7-nitro-5-phenyl-1H-1,4-benzodiazepine with ruthenium tetroxide whereby to obtain 2,3-dihydro-7-nitro-5-phenyl-2H-1,4-benzodiazepin-2-one.

7. A process as defined in claim 1 which comprises oxidizing a compound of the formula 7-halo-1,3,4,5-tetrahydro-5-phenyl-2H-1,4-benzodiazepin-2-one with ruthenium tetroxide whereby to prepare 7-halo-2,3-dihydro-5-phenyl-2H-1,4-benzodiazepin-2-one.

8. A process as defined in claim 1 which comprises oxidizing a compound of the formula 7-chloro-1,3,4,5-tetrahydro-5-phenyl-2H-1,4-benzodiazepin-2-one with ruthenium tetroxide whereby to prepare 7-chloro-2,3-dihydro-5-phenyl-2H-1,4-benzodiazepin-2-one.
